COAXIAL DUAL-UNIT ELECTRODYNAMIC
LOUD-SPEAKERHarry F. Olson, Princeton, and John Preston,
Metedeconk, N. J., assignors to Radio Corpora-
tion of America, a corporation of Delaware

Application April 29, 1949, Serial No. 90,464

4 Claims. (Cl. 179—116)

1

Our present invention relates to signal trans-
lating apparatus, and more particularly to an
improvement in dynamic loudspeakers of the
duo-cone type.

In the field of sound reproduction, the duo-
cone, dynamic loudspeaker has played an
important part in extending the frequency
response range over which sound may be repro-
duced efficiently. Among the different types of
duo-cone loudspeakers which have been designed
and built in the past is that which is particularly
described in U. S. Patent 2,426,948, issued to
applicant J. Preston on September 2, 1947. In
this loudspeaker, the high frequency cone is
coaxially mounted within the low frequency cone,
and both cones are driven by separate voice coils
disposed in a magnetic field, the system oper-
ating in a well known manner. A loudspeaker
such as that disclosed in the above-mentioned
patent, while having a much higher high fre-
quency response than conventional, single-cone
loudspeakers, is quite expensive, however. In an
effort to provide an improved loudspeaker of this
type, we have made certain changes and improve-
ments which result in a simpler and less expensive
construction. Thus, one of the objects of our
present invention is to provide an improved,
simplified, more efficient construction for a loud-
speaker of the duo-cone type.

It is another object of our invention to pro-
vide an improved construction for the vibratory
system of a duo-cone loudspeaker.

It is also an object of our present invention
to provide an improved dynamic type loudspeaker
which will cover an extended range of useful
audio frequencies over that covered by conven-
tional single-cone loudspeakers, yet which will
be less expensive than a duo-cone loudspeaker
such as that disclosed in the above-identified
Patent No. 2,426,948.

It is still another object of our present inven-
tion to provide a duo-cone loudspeaker of the
dynamic type which is simple in construction,
highly efficient in use, and which can be pro-
duced at a minimum of cost.

In accordance with our present invention, we
provide a loudspeaker with two separately driven
diaphragms, one a large, cone-type diaphragm
driven by a large voice coil for reproducing sig-
nals in the low frequency range, and the other
a small, cone-type diaphragm driven by a small
voice coil for reproducing signals in the high
frequency range. The cones and voice coils are
disposed in concentric, nested, overlapping,
spaced relation, with the base of the small cone
coupled to the inside surface of the large cone

2

by a suitable compliant coupling. The small ends
of both cones are supported from the magnetic
structure by suitable, compliant, suspension
members which also serve to center the voice coils
in the air gaps provided in the magnetic struc-
ture. The base of the large cone is suspended,
in well known manner, from a dish-pan type sup-
port attached to the magnetic structure. For
the purpose of preventing vibrations of the large
cone from being transmitted to the small cone,
the compliance of the center suspension of the
small cone is small and relatively stiff compared
to the compliance of the base suspension of the
small cone. In addition, vents are provided in
the large cone for the space between the small
and large cones. A bridge-type magnetic struc-
ture, similar to that disclosed in our copending
application, Serial Number 51,962, filed Septem-
ber 30, 1948, makes it possible to supply the two
air gaps from a single magnet.

The novel features of our invention, as well as
additional objects and advantages thereof, will
be better understood from the following detailed
description of a single embodiment thereof when
read in connection with the accompanying
drawing, in which

Figure 1 is a side view in section, taken
through the center, of a duo-cone loudspeaker in
accordance with our present invention.

Figure 2 is an enlarged plan view in section,
taken on the line 2—2 of Figure 1.

Figure 3 is a wiring diagram of an electrical
circuit corresponding to the mechanical network
of the vibrating system of the loudspeaker shown
in Figure 1, and

Figure 4 is a curve showing the frequency
response characteristic of a duo-cone loudspeaker
in accordance with our present invention and
mounted on a flat baffle.

Referring more particularly to the drawing,
40 wherein similar reference characters designate
corresponding parts throughout, there is shown
a loudspeaker system having a pair of nested,
overlapping, truncated cones 1, 3 which are
mounted in concentric, spaced relation. The
45 outer cone 1 is comparatively large and is par-
ticularly adapted for reproducing low frequency
signals, while the inner cone 3 is comparatively
small and is particularly adapted for reproducing
high frequency signals. The cones 1, 3 are con-
50 nected, respectively, at their apex ends to voice
coil forms 5, 6 which have voice coils 7, 8 dis-
posed, respectively, on their outer surfaces.

For producing a magnetic field, there is pro-
vided a suitable magnetic structure 9 which may
55 be of the type disclosed and claimed in our above-

identified copending application which comprises a yoke 11 and a front plate 13 attached to the ends of the yoke, the front plate having a central, annular aperture 15 therein. A permanent magnet 17 has one end 18 thereof mounted on the base 19 of the yoke 11, with a solid, central cylindrical pole piece 21 disposed on the opposite end 23 thereof and extending through the aperture 15. Also mounted on the end 23 is another cylindrical pole piece 25 which is disposed in spaced relation to the pole piece 21 so as to provide an inner annular air gap 27 therebetween. The pole piece 25 extends through the front plate aperture 15 also in spaced relation to the front plate 13 so as to provide an outer air gap 29 therebetween. An annular, cup-shaped, dust ring 30 of non-magnetic material is secured to the rear surface 32 of the front plate 13 by any suitable means. The annular dust ring 30 has a central aperture 34 through which the pole piece 25 extends in close fitting relation for the purpose of preventing dust particles from entering the outer air gap 29. While the magnet 9, as illustrated in the drawing, is of permanent magnet construction, it could, of course, be of the electro-magnet type.

Attached to the front plate 13 is a dishpan support 31 for mounting the cone diaphragm 1 of the loudspeaker. The circumferentially extending, radially corrugated base portion 33 of the cone 1 is attached to a flanged portion 35 of the dishpan support 31 by any suitable means. The voice coil form 5, which is attached to the apex end 37 of the cone 1, is supported by a flexible spider or corrugated centering member 39, the purpose of which is to maintain the voice coil 7 centered in the outer air gap 29. The outer periphery 40 of the spider 39 is connected to the dishpan support 31 by any suitable means.

The base portion 41 of the small cone 3 is circumferentially corrugated similar to the large cone base portion 33 and has its periphery 43 attached by suitable means to the inner surface 45 of the cone 1, thus eliminating the need of a dishpan support for the small cone 3. The apex end 47 of the small cone 3 is attached to a circular disc or center suspension 49 which is securely fastened to a bushing 50 attached to the end 51 of the center pole piece 21 by means of a screw 52, the disc 49 maintaining the voice coil 8 centered in the air gap 27. For conveniently connecting the voice coil 8 of the cone 3 to the output stage of an audio amplifier, there is attached to the cylindrical pole piece 25 a terminal strip 53 which is provided with a pair of terminals 55 to which the small cone voice coil leads 57 are attached. Electrical leads 59 from the audio amplifier output stage extend through apertures 61, 63 provided in the pole piece 25 and are connected to the terminals 55 on the strip 53.

In order to keep vibrations of the large cone 1 from being transmitted to the small cone 3, certain structural details must be observed. Reference is made to the vibrating system mechanical network illustrated in Figure 3, wherein:

f_1 =the driving force in the low frequency voice coil;

f_2 =the driving force in the high frequency voice coil;

m_1 =the mass of the low frequency cone and coil;

m_2 =the mass of the high frequency cone and coil;

m_3 =the mass of air in the vent holes 67 (referred to more particularly hereinafter) in the low frequency cone;

C_{M1} =the compliance of the outer suspension system of the low frequency cone;

C_{M2} =the compliance of the centering suspension of the low frequency cone;

5 C_{M3} =the compliance of the centering suspension of the high frequency cone;

C_{M4} =the compliance of the outer suspension system of the high frequency cone; and

10 C_{M5} =the compliance of the cavity 65 (referred to more particularly hereinafter) between the low and high frequency cones.

It will be observed from this diagram that the above-mentioned objective can be attained by

15 making the compliance C_{M3} of the center suspension 49 of the small cone 3 very small compared to the compliance C_{M4} of the small cone outside or base suspension 41. That is, the center suspen-

20 sion member 49 should be relatively stiff compared to the base suspension 41. In addition thereto, it is also necessary to vent the space 65 between the large cone 1 and the small cone 3, in order to compensate for the stiffness of the air in the space 65. Thus, by providing a plu-

25 rality of apertures or vent holes 67 in the large cone 1 between its apex end 37 and the point at which the small cone periphery 43 is attached

30 to the large cone inner surface 45, a mass m_3 (defined above) is placed in shunt with the compliance C_{M5} of the cavity 65. The size of the apertures 67 is dependent upon the volume of

35 the cavity or space 65, that is, they should be of a size such that they will provide an impedance which is small compared to the impedance of the cavity or space 65. For the purpose of

keeping dust particles from entering the inner air gap 27 through the apertures 67, suitable screens 69, which may be made of porous, bakenized cloth, are disposed over the apertures 67.

From the foregoing description, it will be ap-

40 parent to those persons skilled in the art that we have provided an improved loudspeaker which is capable of reproducing signals over an extended audio frequency range. For example, the re-

45 sponse from one loudspeaker, which was con-

50 structed in accordance with our present inven-

55 tion and was provided with a flat baffle having dimensions approximately six feet by six feet, covered a frequency range of approximately 50

50 to 11,000 cycles per second, as shown by the re-

55 sponse frequency characteristic curve 71 illus-

60 trated in Figure 4 of the drawing. Although we have shown and described but a single modi-

55 fication of our present invention, it will, no

55 doubt, be apparent to those persons skilled in

60 the art that other modifications, as well as changes in the particular one described above,

are possible within the spirit of our invention. Therefore, we desire that the particular form of

60 our invention described herein shall be con-

sidered as illustrative and not as limiting.

What is claimed is:

1. In a loudspeaker having means for converting electrical oscillations into sound waves, a plurality of cone shaped diaphragms operatively associated with said means, said diaphragms being mounted for independent vibratory movement and being concentrically ar-

70 ranged, means supporting said diaphragms in

75 spaced apart relation one within the other, means including said supporting means for en-

closing an air space between said diaphragms, and means in one of said diaphragms for vent-

ing said air space thereby to prevent vibrations

75 of one of said diaphragms from being trans-

mitted by the air in said space to the other of said diaphragms.

2. The invention set forth in claim 1 wherein said diaphragms are of relatively lesser and greater diameter and particularly effective, respectively, to reproduce higher and lower audio frequencies, and wherein said supporting means includes a compliant coupling attached to the base periphery of said smaller diaphragm, said smaller diaphragm being disposed within said larger diaphragm and said compliant coupling being attached to the inner surface of said larger diaphragm, and wherein said venting means comprises at least one aperture provided in said larger diaphragm.

3. The invention set forth in claim 2 wherein said aperture is of a size such that it will provide an impedance which is small compared to the impedance of said air space.

4. The invention set forth in claim 2 and wherein screen-like material is disposed over said aperture.
